CASE FILLING MACHINE

Carl L. Day and Wilmer D. Regnier, Baltimore, Md., assignors to Crown Cork & Seal Company, Inc., Baltimore, Md., a corporation of New York

Application November 16, 1953, Serial No. 392,131

51 Claims. (Cl. 53—61)

The present invention relates to case filling machines and, more particularly, to machines for placing containers such as bottles in cases or cartons.

The machine disclosed herein is of the type disclosed in the application of Allan C. Davis, Serial No. 192,210, filed October 26, 1950 for Case Filling Machine, now Patent No. 2,701,085, issued February 1, 1955.

The embodiment of the invention hereinafter disclosed is described in connection with the positioning of bottles in open-topped cases or cartons. However, it will be understood from the following objects and description that the invention is applicable to the handling of containers or articles other than bottles, and to the placing of articles in packages other than open-topped cases or cartons.

An object of the invention is to provide arrangements to enable a plurality of rows of articles to be simultaneously delivered to a case filling machine or the like.

Another object of the invention is the provision of means to form a plurality of rows of articles from a smaller number of rows.

A further object of the invention is the provision of conveyor structure suitable for moving one or more rows of articles to a case filling machine or other machine adapted to handle articles.

Still another object of the invention is the provision of a mechanism operable to move a group of articles from one supporting area to another supporting area and which will enable the articles to be spaced apart during such movement.

A further object of the invention is the provision of means to carry articles downwardly to a case, with means of optimum simplicity to control the dropping of the articles from the carrier during downward movement.

Another object of the invention is the provision of means to clamp and center a case and which is of optimum efficiency and simplicity.

Still another object of the invention is the provision of an article holder for use in lowering articles to a case, and which article holder is of simple construction and readily can be assembled and repaired.

Still another object of the invention is the provision of controls for a case filling machine which will be certain in action and of such design that the cycle of operation of the machine will be automatically controlled.

Other objects and advantages of the invention will be apparent from the following specification and accompanying drawings.

Referring to the drawings:

Figure 1 is a plan view of the case filling machine, the front of the machine being at the left;

Figures 2 and 3 are plan views of successive portions of the bottle infeed conveyor structure. If the upper edge of the sheet bearing Figures 2 and 3 is placed against the lower edge of the sheet bearing Figure 1, and with the arrows 2 of the thus opposed edges of the sheets in registry, the manner of delivering bottles from the Figure 2 conveyor portion to the conveyor portion of Figure 1 will be apparent. Bottles initially delivered to the con-

2

veyor structure of Figure 3 continue movement upon the conveyor structure of Figure 2 and then move to the conveyor structure of Figure 1;

Figure 4 is a front elevation of the machine with the bottle carrier in elevated position, the view looking toward Figure 1 from the left;

Figure 5 is a view similar to Figure 4 but with the bottle carrier in lowered position;

Figure 6 shows the machine in side elevation, the view showing the bottle conveyor in vertical section on the line 6—6 of Figure 2. It will be noted that Figure 6 is taken looking toward Figure 1 from the bottom edge of that figure and also looks toward Figure 4 from the right;

Figure 7 is a left hand elevation of the machine, the view looking toward Figure 1 from the top edge of that view and looking toward Figure 4 from the left;

Figure 8 is a plan view showing the two container supporting areas of the machine and with the bottle pushing mechanism partially advanced from the position thereof illustrated in Figure 1;

Figure 9 shows the bottle pushing mechanism on a larger scale than Figure 8, the view being in plan with the top cover plate removed, and showing the parts in the position they occupy when the pushing stroke has started;

Figure 10 is a plan view of the machine with the bottle pushing mechanism at the extreme end of its pushing stroke;

Figure 11 is a view similar to Figure 9 but with the bottle detector plungers in normal or non-pushing position;

Figure 12 views Figure 11 from the bottom edge of the latter figure and the portions shown in section generally are taken on the line 12—12 of Figure 11;

Figure 13 is a fragmentary detail of a portion of the Figure 11 structure, the view looking toward Figure 11 from the direction of the arrow 13;

Figure 14 is a horizontal sectional view on the line 14—14 of Figure 5;

Figure 15 is a vertical sectional view on the line 15—15 of Figure 1, with portions broken away. The view includes a solid line showing of the bottle carrier in its normal or raised position and a dotted line showing of the carrier in lowered position;

Figure 16 is a vertical sectional view of the upper portion of the machine on the line 16—16 of Figure 10, the view showing the bottle carrier in vertical section on the line 16A—16A of Figure 17;

Figure 17 is a vertical section of the upper portion of the machine, the view being on the line 17—17 of Figure 16;

Figure 18 is a vertical sectional view in the same plane as Figure 17, the view showing the lower portion of the machine with the bottle carrier in lowered position;

Figure 19 shows the case conveyor and case centering means in plan, the view being taken on the line 19—19 of Figure 4;

Figure 20 is a fragmentary detail of the case clamping and centering mechanism, the view showing that mechanism in plan;

Figure 21 is an elevation of a bottle holding device used in the bottle carrier, the holder being shown in bottle dropping position;

Figure 22 is a view looking toward Figure 21 from the right;

Figure 23 is a top plan view of the holder of Figures 21 and 22;

Figure 24 is a vertical section on the line 24—24 of Figure 22;

Figure 25 is a perspective view of the bottle holder of Figures 21 to 24;

Figure 26 shows the bottle infeed gate mechanism

in detail, the view being taken on the line 26—26 of Figure 1;

Figure 27 is a plan view of the bottle infeed mechanism of Figure 26 with the top wall removed;

Figure 28 is a fragmentary view of the case clamping and centering mechanism, the view looking toward the Figure 19 structure from the direction of the arrow 28 in Figure 19, and

Figures 29 and 30, when positioned with the top edge of Figure 28 adjacent the lower edge of Figure 27, diagrammatically show the machine and its control devices.

The operation and construction of the apparatus generally may be described as follows:

Referring to Figure 3, each of the conveyors 50 and 52 moves bottles B to be cased toward the machine in a single row from one of two filling machines or other sources of containers to be cased. The bottles moving on the conveyors 50 and 52 will be formed into a double row as they are guided on to a third conveyor 56 by the converging portion 55 of the guide rails 54 of Figure 3 so that, as shown in Figure 3, the containers of the two rows on conveyor 56 may be abreast, the guide rails 54 along conveyor 56 being spaced apart a distance slightly greater than the diameter of two containers. It will be understood that if a single filling machine or other source has a sufficiently high output of bottles, such output can be placed directly upon the conveyor 56 by a single-line conveyor.

Referring to Figure 2, the lines of containers moving on the conveyor 56 will be delivered to a fixed distributor plate 58 and pointed divider 60 which will form the containers into two double rows as subsequently described, so that four rows of containers will move from distributor plate 58 on the wide conveyor 62, two rows on each side of the divider 60. Divider 60 has a flat spring plate or deflector 61 extending in a V from each diverging surface thereof, the plates 61 tending to deflect bottles slightly away from the central dividing wall which continues beyond divider 60. The containers of each double row again may be abreast because the space between each side of divider 60 and the opposite guide rail 54 is wide enough to permit two bottles to move abreast. A second distributor plate 64 near the outfeed end of divider 60 will assist in dividing each of these two double rows of containers into two single rows which thereafter continue movement on conveyor 62 between vertically arranged guide plates 66 which, as shown in the lower right hand portion of Figure 1, extend to the gate mechanism 68. As shown in Figure 1, conveyor 62 extends almost across the top of the machine table 70, the upper run of conveyor 62 being flush with the upper surface 72 of the table. As appears from Figure 6, conveyor 62 actually consists of two conveyors moving side by side in synchronism.

As is hereinafter explained, the gates 73 of the gate mechanism 68, shown in more detail in Figures 26 and 27, normally will be open to permit conveyor 62 to move containers through the gate mechanism in four rows and between guide bars 74. As shown in Figure 1, in the embodiment of the machine disclosed herein, each of the four rows formed between the bars 74 will contain six bottles, with the leading bottle of each row adapted to contact with one of four trip plungers 76 forming part of the pusher mechanism 80. Each plunger 76 preferably is under such spring tension that it will not be actuated by pressure of less than twelve bottles thereon, through this pressure may be increased or reduced as desired and depending upon the rate of supply of bottles as well as the rate of supply of cases in which to position the bottles.

As best indicated in Figure 8, the pusher mechanism 80 includes a box like casing 82 reciprocable upon two fixed and horizontal slide rods 84. The guide bars 74 extend from the inner wall 85 of casing 82 to a point adjacent the gate mechanism 68. When the casing 82

of pusher mechanism 80 is in the bottle receiving position shown in Figure 1, the bars 74 will be in alignment with corresponding vertical plates 66 of the infeed gate mechanism. It will be noted from Figure 1 that each trip plunger 76 is midway between two adjacent bars 74.

When the pressure of the four rows of bottles moves all of the plungers 76 from the solid line position of Figure 11 to the position indicated in Figure 11 by the dotted line 76a, mechanism hereinafter described in detail will first cause the gates 73 of gate mechanism 68 to swing from a position in alignment with the guides 66 and bars 74 to the position indicated in Figure 27 to thereby segregate the four rows of six bottles between the bars 74 from the other bottles on conveyor 62, as well as hold back the latter bottles. Then pusher mechanism 80 will move to the left as viewed in Figure 1, that is, toward the front of the machine, to move the bottles from the bottle supporting area provided by conveyor 62 to the bottle supporting area provided by a horizontally movable grid 90. As shown in Figure 15, grid 90 has the upper surface of its bottle supporting bars 92 flush with the table surface 72. During the first portion of this movement of the pusher mechanism 80, the plungers 76 will be further retracted by means hereinafter described to the position indicated in Figure 8 at 76b so that the outer ends of the plungers will be flush with the face 94 of the pusher mechanism casing wall 85.

This further reaction of the plungers 76 will enable bottles to move lengthwise of each row and the bars 74 when the bottles come into engagement with guide bars 100 fixed to table 70 and which extend across and above grid 90 parallel to the bottle supporting bars 92 of the grid. In more detail, it will be apparent from Figure 8 (which shows the plungers 76 fully retracted) that as the bottles are moved to the left in that figure to be positioned on grid 90, the six bottles in each of the four rows will be forced apart lengthwise of the rows by the stationary guide bars 100. The retraction of the plungers 76 permits the bottles to rearrange themselves to meet this condition. The guide bars 100 have their inlet ends arranged along a shallow V, with the end 100a of the center bar 100 extending closest to the approaching bottles. As shown in Figure 16, the fixed guide bars 100 are arranged in upper and lower sets, the upper set engaging the top portions of the bottles and the lower set engaging the base portions of the bottles.

Figure 10 shows the pusher 80 at the limit of its forward or bottle pushing stroke. It will be observed from this view that the surface 94 of the pusher mechanism casing 82 cooperates with the nearest bar 100 to guide the adjacent line of bottles.

In accordance with the practice described in said Davis application, the grid 90 shown in Figure 16 now will be moved to the left as viewed in that figure so that the bottle supporting bars 92 of the grid will be brought into vertical alignment with the lower set of fixed guide bars 100. Hence, the bottles will drop through grid 90 and into the holders 102 of the basket of carrier 110 which, at this moment, will be in uppermost position. By suitable circuit arrangements hereinafter described, after carrier 110 has moved down far enough that the bottles will be clear of the pusher bars 74, the pusher mechanism 80 will return to the right in Figure 1 to bottle receiving position above conveyor 62. During such return movement, the plungers 76 will be restored to their outermost position and when pusher mechanism 80 reaches its normal position shown in Figure 1, the gate mechanism 68 will reopen to permit conveyor 62 to again fill the bottle supporting area defined by the arms 74 of pusher mechanism 80.

Referring to Figure 17, at the time that the bottles drop into the holders 102 of the basket 110, the rotat-

able cam rods 112 best illustrated in Figure 16 will be in the position shown in Figure 17 to thereby hold two opposed bottle holder blades 114 toward each other to prevent the bottles from dropping between them. However, when carrier 110 lowers to the dotted-line position of Figure 15, a latch 116 pivoted on bottle carrier 110 will strike a trip 118 fixed to the machine frame. This movement of latch 116 will release a lever 120 fixed to one of the cam rods 112 so that lever 120 will swing by the action of spring 122 (Figure 15) to the dotted line position of Figure 15. Because the cam rods 112 are interconnected, all of them will be rotated to the position shown in Figure 18 so that the blades 114 may be opened by the weight of the bottles to the position shown in Figure 18 and the bottles will drop through the holders 102 into a case C. When the bottles have dropped, counterweight 124 (Figure 18) and air pressure in a cylinder 125 (Figure 4) will raise carrier 110 to the solid line position of Figure 15. During upward travel of carrier 110, cam 126 fixed to the machine frame will restore lever 120 to normal position to be engaged by latch 116.

As is hereinafter explained in detail, suitable controls are provided to prevent grid 90 from moving to bottle dropping position unless the bottle carrier 110 is in the solid line raised position of Figure 15. Also, unless a case is clamped beneath bottle carrier 110, the latter cannot automatically lower.

Referring to Figure 19, in the embodiment of the machine illustrated cases C to receive the bottles B are moved into the machine by the case conveyor 130 which moves the cases C from right to left with respect to Figure 19. Conveyor 130 appears at the lower left in Figure 1 and moves cases upwardly with respect to that figure. The cases C move into the machine between fixed guides 132 and 134 and when a case C actuates the case clamp switch 136, the case clamping and centering mechanism 140 best shown in Figures 19, 20 and 28 is actuated so that its pusher plate 142 will push the case from the dot-dash line position of Figure 19 to the solid line position of the same figure. At the same time, the clamping arms 144 forming part of the mechanism 140 will be moved from the solid line position of Figure 19 to the dotted line position of the same figure to thereby accurately center the case with respect to the vertically movable bottle carrier 110 and hold the case in such centered position. As soon as the bottle carrier 110 drops its bottles B and begins upward movement, the case C will be released by return of the clamping arms 144 and pusher plate 142 to the solid line position of Figure 19. Then case C may move to the left in Figure 19 upon case conveyor 130 and between the guides 146 and 148. So long as the case is contacting with the clamp arm safety switch 150 of Figure 19, the case clamping and centering mechanism 140 cannot be moved from the solid line position of Figure 19, thereby preventing an outgoing case being engaged a second time by the mechanism 140.

It will be noted that in the machine disclosed, both bottles B and cases C enter the machine from the right. However, the machine readily can be constructed to receive both bottles and cases from the left, or to receive bottles from either direction and cases from the opposite direction. This capability renders the design widely useful to meet bottle plant layouts.

The detailed construction and operation of each mechanism of the machine is hereinafter described under appropriate headings.

Bottle infeed

Referring to Figure 3, the bottle conveyors 50 and 52 may be of the usual flat link straight-line type used for the handling of bottles in bottling plants and the bottles may be placed thereon by the outfeed conveyor of each of two filling machines or other source of bottles to be

cased. Each of the conveyors 50 and 52 moves in a fixed supporting framework 161 in which a transverse shaft 160 is journaled to carry spaced sprocket wheels 162 to support one end of the runs of the respective conveyors 50 and 52. The wider conveyor 56 extends a short distance between the outfeed ends of the conveyors 50 and 52 and with the inside lateral edges of the conveyors 50 and 52 closely adjacent the edges of conveyor 56. The infeed end of conveyor 56 moves about a sprocket 164 fixed to a shaft 166 spaced from shaft 160 in framework 161. The shaft 160 may be driven by a motor, not shown, mounted in framework 161, this motor being operable to drive the conveyors 50 and 52 at about the same linear speed as conveyor 56. As subsequently described, conveyor 56 may be driven by a motor mounted on the casing machine.

The bottles moving along the conveyors 50 and 52 are held in single lines by the guide rails 54 fixed to framework 161 and which converge as shown at 55 in Figure 3 to direct the row of bottles from each of the conveyors 50 and 52 onto the conveyor 56. Alongside conveyor 56 the guide rails 54 are spaced a distance apart slightly greater than twice the diameter of the bottles being handled so that the bottles in the row moving from one single row conveyor 50 or 52 may move directly abreast of those moving from the other single row conveyor if a bottle from conveyor 50 and a bottle from conveyor 52 happen to reach conveyor 56 at the same instant.

As shown in Figure 2, the two rows of bottles may continue upon conveyor 56 and between the guide rails 54 to a relatively thin distributor plate 58 fixed to the frame 161 and having its infeed and outfeed edges bevelled to a knife-edge to permit bottles to readily move from the surface of conveyor 56 and up on plate 58.

The outfeed end of conveyor 56 moves about a sprocket wheel 169 secured to a shaft 170 journaled beneath plate 58. Sprockets 172 also are provided on a shaft 174 beneath the outfeed portion of plate 58 to support the wider conveyor 62, which will move bottles from the outfeed edge of the plate 58. The shafts 170 and 174 are connected by a sprocket chain 176. Conveyor 56 will move at twice, or slightly less than twice, the linear speed of conveyor 62 but, in any event, conveyor 56 will not move the bottles so fast that they will fall when they reach the distributor plate 58. The speed relationship mentioned will maintain an entirely adequate supply of bottles on conveyor 62, which has twice the width of conveyor 56. The drive for both conveyors 56 and 62 may be imparted to conveyor 62 by a motor beneath table 70 of the bottle casing machine. The casing machine may operate to case at least three hundred six ounce bottles per minute and the conveyors 50, 52 and 56 naturally must operate at such speed as to place a like number of bottles on conveyor 62.

As has been indicated above, alongside conveyor 56 the guide rails 54 are spaced apart a distance slightly greater than twice the diameter of the bottles being handled. Therefore, bottles may move along conveyor 56 either abreast as indicated in Figures 3 and 2, or slightly staggered.

At any rate, bottles on the conveyors 50, 52 and 56 usually will be spaced slightly behind one another because they will have left the filling machine in that relation. When a bottle move upon the distributor plate 58, it will tend to stop forward movement, but will be pushed forward upon the plate by the following bottle. Because the bottle supporting surface of plate 58 is smooth and polished, if the supply of bottles by conveyor 56 is uninterrupted, bottles will be pushed across plate 58 as rapidly as they move with conveyor 56.

A bottle pushed off the outfeed edge of distributor plate 58 immediately will contact with the wider conveyor 62 to be carried forward. The divider 60 is positioned midway of the width of the outfeed edge of distributor plate 58 and the guide rails 54 begin to diverge at the divider point. As indicated in Figure 6, divider 60 is fixed to

the upper edge of a vertical plate 178 secured to framework 161. As also appears from this figure, conveyor 62 actually is formed of two flat link conveyors, one on each side of divider 60 and both moving together at the same speed. As shown in Figure 2, divider 60 is at the infeed end of a vertically extending divider plate 180 having a length approximately twelve times the bottle diameter to enable a substantial number of bottles to be positioned and accumulate alongside thereof.

Distributor plate 58 may have a length about four times the diameter of the bottles being handled but divider 60 has its knife-like point or apex about one bottle diameter in advance of the outfeed edge of plate 58. The plates 61 of flat spring metal which are secured to the diverging faces of divider 60 diverge in continuation of the divider faces and terminate slightly beyond the outfeed edge of plate 58.

Because bottles move upon distributor plate 58 in two rows, they will move across and off it in much the same relationship except insofar as some variability exists on the bottom or wall of a bottle, or in the position of an infeed bottle. Therefore, bottles entering the left-hand portion of plate 58 will move across and off that portion of the plate and to the left-hand side of divider 60 while those entering the right-hand portion of the divider will continue upon that portion and to the right of the divider.

A particular advantage of using a fixed distributor plate such as 58 is that if a bottle should happen to be pushed laterally while on plate 58 so as to be directly in alignment with the point of divider 60, a succeeding bottle will push the first bottle to one side or the other of the divider so that no jam can occur. Because plate 60 is of substantial length, if a gap occurs in either of the two continuous and contacting rows normally moving across it, so that one or more bottles become laterally deflected by the pressure of following bottles, there still will be an adequate remaining length of plate 58 on which the bottles may push one another about so that usually at least two bottles will leave plate 58 at the same instant. In short, plate 58 not only serves to distribute bottles on each side of divider 60, but also has an accumulating effect in that it enables gaps in the rows to be closed, because no bottle can leave plate 58 until it is pushed therefrom by rearward contacting bottles including one or more bottles still on conveyor 56. Also, as stated above, it will be almost impossible for two immediately adjacent bottles to remain in single line formation directly in alignment with divider 60 and, in any event, the then following bottles will break up that alignment by forward and lateral pressure.

The guide rails 54 begin to diverge about one bottle diameter inwardly of the outfeed edge of plate 58 and at the outfeed edge are far enough apart so that two bottles abreast may move off plate 58 on each side of divider 60. Bottles initially will move onto conveyor 62 in two rows, one on each side of divider 60, but the deflector plates 61 will direct each row slightly away from divider plate 180 as shown at B¹ in Figure 2. The purpose of this is hereinafter described under the heading "Control circuits."

Conveyor 62 has a second distributor plate 64 extending across it at the infeed end of the guide plate 66, plates 64 having a length approximately three times the bottle diameter and having its outfeed edge positioned at the outfeed end of divider plate 180. When the bottles reach plate 64, the action will be much the same as occurred at plate 58. That is, while a bottle will tend to stop when it first contacts with plate 64, it will be pushed forward by succeeding bottles moved by conveyor 62. The guide plates 66 are supported by one or more cross-bars 160 suitably supported and spaced above the surface of conveyor 62 so that bottles may move beneath the bars 160. The centermost of the five guide plates 66 is in alignment with the guide plate 180 and the remaining guide plates 66 are separated from each other by a dis-

tance very slightly greater than the diameter of the bottles being handled. The outfeed end of divider plate 180 is reduced in thickness to have the same thickness as the centrally disposed plate of the vertically extending guide plates 66.

The guide plates 66 terminate closely adjacent the outfeed edge of the distributor plate 64. Bottles will move across distributor plate 64 in four rows, two on each side of divider plate 180, and each row will tend to move directly between two adjacent guide plates 66.

It will be observed that bottles cannot abut the ends of any of the guide plates 66 except the two designated 66a which are immediately adjacent the center guide plate 66. The ends of these two guide plates may be beveled as indicated at 182 but, in any event, as has been pointed out with respect to the distributor plate 58 and divider 60, should a bottle advance directly toward the end 182 of a plate 66a, the forward and lateral pressure exerted thereon by succeeding bottles will insure that such bottle will be moved clear of that end 182 and between two adjacent guide plates 66 or 66a. As has been stated above, the vertical guide plates terminate at the gate mechanism 68.

As is indicated in Figure 1, the conveyor 62 continues across the upper portion of the table 70, with the upper surface of the conveyor flush with the surface 72 of the table. Suitable sprocket wheels to drive conveyor 62 and direct its lower run back toward the sprocket 172 beneath distributor plate 58 may be positioned beneath table 70 and, more particularly, beneath the pusher mechanism 80. A motor, not shown, will drive the table mounted sprocket wheels.

Bottle gate mechanism

The gate mechanism 68 to hold back the four lines of bottles B on the conveyor 62 during operation of the pusher mechanism 80 is best illustrated in Figures 26 and 27 though it also appears in Figure 6 and its location best can be ascertained from Figure 1.

Referring to Figure 26, gate mechanism 68 is supported upon two plate-like vertical elements 190 and 191 which stand upon the surface 72 of table 70, one on each side of the path of the conveyor 62. As has been stated above, gate mechanism 68 is positioned at the outfeed ends of the guide plates 66 and immediately adjacent the infeed ends of the pusher bars 74.

A horizontally arranged flat plate 194 bridges the adjacent ends of the elements 190 and 191 at sufficient height above conveyor 62 that the bottles to be cased may move freely below plate 194. Plate 194 has five journal bosses or collars 196 welded in apertures therethrough, with each collar in alignment with one of the divider plates 66. A rod 198 is rotatable in each collar, the portion of each rod 198 below its boss being milled to provide a relatively thin and narrow vertical plate forming a gate 73. Each gate 73 extends closely adjacent the upper surface of conveyor 62. Above horizontal plate 194, each rod 198 has a lever 200 secured thereto, the lever including a collar portion 202 secured to the rod 198 by a pin 204. The free ends of the five levers 200 are pivotally connected to an operating bar 206 which extends above and parallel to the horizontal plate 194 and is secured to a piston rod 208 which has a piston, not shown, secured thereto within the gate operating cylinder 210.

Figures 26 and 27 show the gates 73 in closed position so that each stands at an acute angle to the guide plates 66. In this position, the gates 73 will prevent bottles from moving into the bottle-supporting area in which the pusher mechanism 80 receives bottles. That is, although the conveyor 62, being continuously driven, will move beneath the bottles which are outwardly of the gate mechanism 68, the gates 73 will hold the bottles stationary.

When the gate operating cylinder 210 moves the operating bar 206 to the left in Figures 1, 6 and 27, the gates

73 will be turned in a clockwise direction (Figure 27) to lie in the planes of the corresponding guide plates 66 and pusher bars 74 so that bottles outwardly of the gate mechanism may move between the pusher bars 74 with the conveyor 62. As is hereinafter explained, when the operating bar 206 is in the gate closing position illustrated in Figure 27, the right hand end of bar 206 will close an electrical switch 212 mounted in a casing secured to the supporting plate 194. When the operating bar moves to the left to open the gates 73, switch 212 will open.

The bottle pusher mechanism 80

The bottle pusher mechanism 80 is shown in general relation to the top of the machine in Figure 1, this view showing the pusher mechanism in normal or bottle-receiving position. Figure 8 shows the pusher mechanism during the initial portion of its pushing stroke, and Figure 10 shows it at the completion of its pushing stroke. Figures 11 and 12 illustrate the details of the mechanism in the position they occupy before actuation by bottles, and Figure 9 shows the details of the mechanism in the position they occupy during the pushing stroke.

Referring to Figure 11, the bottle pusher mechanism 80 includes a box-like casing 82 which has bearing apertures 220 in its end walls 221 and 222 to support the casing for reciprocable movement on the rods 84 shown in Figure 8. The slide rods extend from front to rear of the top of the table 70, being supported above the table by brackets 223 and 224 best shown in Figure 7.

As shown in Figures 9, 11 and 12, a vertical plate 228 is fixed within the casing 82 to lie parallel to the inner wall 85, that is, the wall facing the gate mechanism 73 and incoming bottles. Plate 228 and wall 85 are provided with aligned apertures 230 and 231, respectively, in which the plungers 76 move. Each of the four plungers 76 includes a bottle-engageable portion designated 232 of substantial diameter and of such length that in normal position its outer end 233 will lie adjacent the inner side of the plate 228. The portion 232 has a collar 234 pinned thereto inwardly of the casing wall 85 and a coil spring 236 extends between collar 234 and a washer or collar 237 which bears on plate 228. As is hereinafter explained, spring 236 is of sufficient strength to hold the corresponding plunger 76 in the position of Figure 11 against the pressure of a predetermined number of bottles, for example, twelve.

Outwardly of the enlarged portion 232, each plunger 76 includes a portion 240 of small diameter and which is of relatively short length. Beyond reduced portion 240, each plunger 76 is again enlarged as indicated at 242.

When the plungers 76 are in the normal position shown in Figure 11, the inner ends of the enlarged portions 242 will lie in notches 244 on the upper surface of a trigger bar 246 (Figure 12). Trigger bar 246 is horizontally reciprocable in openings 247 in the end walls 221 and 222 of the casing 80 and is urged to the right from the position shown in Figures 11 and 12 by a coil spring 248 extending between a pin 250 on the outer wall 252 of casing 82 and a pin 254 secured to the outer face of trigger bar 246. The movement of trigger bar 246 further may be guided by a bolt 256 secured to plate 228 and extending through a slot 258 in the trigger bar.

As has been stated above, when a predetermined number of bottles presses upon a plunger 76, the inner end of the plunger will move to the position indicated by the dotted line 76a of Figures 9 and 11. In order to further retract the plungers 76 to the position indicated at 76b in Figure 9, a pull bar 260 extends horizontally through slots 262 in the outer ends of the plungers. Bar 260 is guided in a horizontal plane toward and away from the outer wall 252 of casing 82 by means of pins or bolts 264 movable in slots 266 formed in brackets 268 secured to the wall 263. As indicated in Figure 11, the inner ends 265 of the slots 262 normally are spaced from the

opposed edge of the pull bar 260, the opposite ends of the slots then contacting with the outer edge of the pull bar.

Bar 260 is arranged to be moved to the position of Figure 9 by the action of levers 270 pivotally connected to bar 260 by pins 272. The levers 270 extend from bar 260 and into casing 82 through openings 271 in the casing wall 252, the inner ends of the levers 270 being bifurcated as shown in Figure 12 to be pivotally connected at 273 to a slide rod 274 which is reciprocable in apertures 276 in the casing end walls 221 and 222. As is hereinafter explained, the movement of rod 274 to actuate the levers 270 is effected by means of a drive carriage 280 which, as shown in Figures 1 and 8, is slidable in front of casing 82 on the guide rods 84.

As has been stated above, the bottle pushing bars or plates 74 extend toward the gate mechanism 68 from the inner wall 85 of the pusher casing 82. As shown in Figure 16, these bars are of substantial height so as to bear against the greater portion of the body of a bottle. As indicated in Figure 8, the bars 74 are spaced apart by a distance only slightly greater than the diameter of the body of a bottle.

As shown in Figure 1, the table 70 includes a smooth fixed portion 282 between bottle conveyor 62 and the opening 284 in the table in which the grid 90 operates. The fixed guide bars or plates 100 extend from a support 286 at the forward portion of table 70, across opening 284 and partially across the fixed portion 282 of the table upper surface. The pusher mechanism 82 will move the four rows of bottles from conveyor 62 across surface 282 and between the guide bars 100 so that the bottles will stand between the latter and upon the bottle supporting bars 92 of grid 90. As shown in Figure 1, a guide bar 288 parallel to the guide bars 100 will define one side of the path of the line of bottles which will be lowermost in Figure 1. One side of the path of the line of bottles closest to pusher 80 initially will be defined by a plate 290 positioned closely above the surface 72 of table 70. Immediately beyond conveyor 62, the bottle-guiding edge of plate 290 is beveled outwardly as indicated at 292 and thereafter continues parallel to the adjacent guide bar 100 as indicated at 294.

The operation of the bottle feeding or pusher mechanism 80 is as follows:

When a predetermined number of bottles, for example, twelve, is standing on conveyor 62 in each of the rows defined by the guide plates 66 and pusher bars 74, the pressure imparted to the bottles by the movement beneath them of conveyor 62 will force the plunger 76 of each row from the solid line position of Figure 11 to the position indicated by the dotted line 76a. This movement of the plunger will be resisted by the spring 236 and, if rows of six bottles are to be formed, it usually will be desirable to have the springs of such strength that the pressure of at least twelve bottles will be required to move a plunger as described above. It will be noted that this movement of the plungers 76 will bring the ends 265 of the plunger slots 262 into close engagement with the opposed edge of pusher bar 260.

If each of the four rows of bottles does not contain twelve bottles, the four plungers may not move simultaneously, but the supply of bottles normally will be such that at least twelve bottles will stand in each row. At any rate, when all four plungers 76 have been pushed to the position indicated by the dotted line 76a, the outer enlarged portion 242 of each plunger thereby will be moved outwardly (upwardly as viewed in Figure 11) to free portion 242 from the corresponding notch 244 (Figure 12) of the trigger bar 246 and position the reduced portion 240 of the plunger in registry with the trigger bar. In other words, the trigger bar will be unlatched so that spring 248 may move it to the right in Figure 11. Through circuits hereinafter described under the heading "Control circuits," this movement of trigger bar 248 will actuate a switch 298 which will result in

flow of compressed air to the cylinder 210 so that the gates 73 will close. When the gates 73 close, the switch 212 of Figures 26 and 27 will close and, as subsequently explained in connection with the control circuits, compressed air will flow to a fixed cylinder 300 which extends horizontally of the machine above the casing 82 of the pusher mechanism 80, the outer end of cylinder 300 being supported by a bracket 302 fixed to table 70. Cylinder 300 has a piston rod 304 movable therein, the outer end of piston rod 304 being secured to the drive carriage 280. With the drive carriage 280 in its normal or Figure 1 position closely adjacent casing 82, the just-mentioned movement of piston 304 first will move the drive carriage to the left to a position spaced from the casing 82 somewhat as indicated in Figure 8. As has been stated above, the pull rod 274 is fixed to the drive carriage 280 and the movement of the drive carriage away from casing 82 will move pull rod 274 forwardly (to the left in Figure 11) through casing 82 from the position shown in Figure 11 to the position shown in Figure 9. This movement of rod 274 will cause the levers 270 to swing clockwise within casing 82 to thereby force the pull bar 260 away from the pull rod 274 and the outer wall 252 of casing 82, that is, from the position of Figure 11 to that of Figure 9. Hence, the bottle-engaged ends of the plungers 76 will be moved from the position indicated by the dotted line 76a of Figure 9 to the position indicated by the dotted line 76b so that those ends of the plungers now will lie flush with the surface 94 of the inner wall 85 of casing 82.

When the pull rod 274 has been moved to the position relative to casing 82 indicated in Figure 9, bar 260 can have no further movement in casing 82 and, therefore, the pull exerted by drive carriage 280 now will be applied entirely upon casing 82. Hence, casing 82 and the bottle pusher bars 74 will now move toward the front of the machine. This initial movement of casing 82 will permit a switch 306 to close. As subsequently explained, this will hold the gates 73 closed until the pusher mechanism 80 returns to bottle-receiving position.

It will be observed that the movement of the plungers 76 from the position indicated at 76a in Figure 9 to the position 76b of the same figure will provide a space within each row of bottles engaged by the pusher bars 74. Therefore, as the bottles move toward the grid 90, they may separate as required by the guide bars 100.

In order to restore the plungers 76 to the solid line position of Figure 11, it is not only necessary that the pull bar 260 be restored to the position shown in Figure 11 but also that the trigger 246 be restored to the position shown in that figure. In order to accomplish this, a cam mechanism, best shown in Figure 13 and generally designated 310, is mounted on the outer portion of the end wall 221 of the pusher casing 82. Cam mechanism 310 comprises a horizontally extending stub shaft 312 mounted in a sleeve 314 (Figure 11) secured to casing 82.

The outer end of shaft 312 has an arm 315 normally extending downwardly therefrom, and a roller 316 is secured to the free end of this arm. The opposite end of shaft 312 carries a cam 318 including a curved rise 320 and a flat face 322, the flat face normally abutting against a wear plate 323 on the opposed surface of the end wall 221 of casing 82. As is hereinafter described, the surface of curved rise 320 is adapted to engage a roller 324 mounted on a pin fixed to the front end of trigger 246, which extends out of the wall 221 of casing 82.

When the trigger 270 is drawn to the right in Figure 11 by spring 248, its roller 324 will move to the left from the position shown in Figure 13 to thereby come into contact with the opposed curved surface 320 of cam 318 which, at that instant, will be in the position of Figure 13, that is, with its flat face 322 bearing against the wear plate 323 on casing 82. When the casing 82

subsequently moves toward the front of the machine (to the right in Figure 13) the roller 316 of cam mechanism 310 will ride up upon the raised cam bar or surface 330 fixed to the upper surface of table 70. Therefore, trigger 246 will be restored to normal position, that is, its notches 244 will be aligned with the outer enlarged portions 242 of the plungers 76. The cam mechanism 310 will remain in this position during the continued forward movement of casing 82 and during its return movement. In other words, until the final return movement of casing 82 again permits roller 316 to drop from cam 330, the trigger bar 246 will be held in normal position. However, as hereinafter explained, the plungers 76 will not return to their Figure 11 position and through the trigger bar until casing 82 begins return movement.

When the drive carriage 280 reaches the limit of its pushing position illustrated in Figure 10, a downwardly facing cam bar 331 (Figures 1 and 8) will contact with a switch 332, hereinafter described, to cause compressed air to flow to the cylinder 370 (Figure 16) which operates grid 90, so that the grid will move to bottle dropping position. When the bottle carrier 110 then moves down a sufficient distance that the bottles are clear of the pusher arms 74, means hereinafter described will reverse the flow of air to cylinder 304 so that piston 304 will be drawn back into that cylinder. This return movement of piston rod 304 first will cause drive carriage 280 to move closely adjacent carriage 82, thereby pushing the pusher rod 274 from the position within casing 82 shown in Figure 9 to the position shown in Figure 11. This will swing the levers 270 so that the pusher bar 260 will be drawn inwardly, thereby permitting the springs 236 to restore the plungers 76 to the normal position illustrated in Figure 11. Such movement of the plungers will be permitted because the trigger 246 has been restored to normal position as described in the immediately preceding paragraph.

It will be appreciated that once the bottles have dropped into the bottle carrier 110, it is entirely practicable to restore the plungers 76 to normal position. Just before drive carriage 280 and pusher casing 82 return to their normal or bottle-receiving position illustrated in Figure 1, the roller 316 of cam mechanism 310 (Figure 13) will move off cam 330 thereby permitting cam arm 314 to drop to the position of Figure 13 so that its flat face 322 will contact with casing 82. This rotation of the cam is induced by the pull of spring 248 on trigger 246, as well as by the weight of arm 315 and roller 316.

When casing 82 returns to its normal position of Fig. 1, the switches 298 and 306 will return to normal opened position, one result being to open the gates 73 so that bottles can move with conveyor 62 and through the gates to fill the pusher mechanism.

It will be noted that the plungers 76 and gates 73 comprise means to bound the bottle-receiving area of the pusher mechanism 80 and that the plungers 76 are movable to enlarge that area.

The grid mechanism

The grid mechanism 90 provided in the present machine is substantially similar to that disclosed and claimed in said Davis application.

As has been pointed out above, and as is best shown in Figure 16, the fixed bottle guides associated with the grid mechanism 90 are arranged in upper and lower sets. The guides of the lower set are designated 100 and the guides of the upper set are designated 340. The lower guides 100 are of slight height so that they will engage only the base portions of bottles. The pusher plates 74 are provided with notches 341 which will clear the guides 100 as the pusher plates move along the same.

The upper guides 340 are adapted to engage the neck portions of the bottles and, therefore, extend rearwardly

of the machine from a horizontally extending crosspiece 286 secured to posts 342 extending upwardly from the forward portion of the table 70. The crosspiece 286 is vertically adjustable with respect to the posts 342 to thereby enable the top guides 340 to be set to engage bottles of various heights.

The grid 90 includes bottle-supporting bars 92 which extend parallel to the path of movement of the bottles. The bars 92 also are parallel to the guides 100 but it will be noted from Figure 16 that when the grid 90 is in bottle-receiving and supporting position, the bars 92 are not positioned midway between two adjacent guide bars 100 but, instead, are close to one guide bar 100. Therefore, a bottle standing on a guide bar 92 will tend to lean rather than stand upright. The upper guides 340 are so positioned as to permit this slight leaning movement. When the grid opens to permit the bottles to drop, the bottle-supporting bars 92 will be moved to the right of the machine (to the left in Figure 16) so that the grid bars 92 thereby move along the upwardly inclined portion of the base of the bottle.

As is the case with the grid of said Davis application, the present grid includes transversely extending bars 344 which have their upper edges somewhat below the upper edges of the bottle-supporting bars 92. Therefore, when the bottles are pushed along the supporting bars 92 by the pusher plates 74, the upper edges of the transverse bars 344 will be below and clear of the bottle base.

The complete form of the grid 90 is best shown in Figure 1 which omits the upper guide bars 340. It will be observed from Figures 1, 10 and 16 that the two forward and rearward transverse bars 344 are laterally extended beyond the grid proper and, at the right hand side of the machine, are joined by an end piece 346. As shown in Figure 16, end piece 346 is apertured to move on guide rods 348 extending inwardly from a flange 350 depending from the table surface 72. Coil springs 352 may be positioned on the rods 348 to cushion the lateral stroke of the grid. The other end of the grid structure is formed by an end piece 356 which is laterally movable upon two rods 358 fixed in a depending flange 360 at that side of the table opening 284. Coil springs also may be mounted on the rods 358 to cushion the return stroke of the grid and also tend to hold it in bottle-supporting position.

As has been indicated above, when the bottles are to be dropped off of the bottle-supporting bars 92 of the grid, the grid is moved to the right of the machine, that is, downwardly as viewed in Figures 1 and 10 and to the left as viewed in Figure 16. This movement of the grid is accomplished by a piston in a cylinder 362 controlled by a valve and solenoid 370, all best illustrated in Figure 16. The piston of cylinder 362 extends upwardly to a toggle device 374 which normally is in the angled position of Figure 16. When solenoid 370 is energized to move the piston in cylinder 362 upwardly the toggle mechanism will be actuated to a more nearly straight-line position to push the bottle-supporting bars 92 of the grid into alignment with the lower set of bottle guides 100. The result will be that the bottles will drop through the grid and into the bottle holders 102 of bottler carrier 110.

As is best shown in Figures 1 and 5, in order to prevent the grid from being moved to bottle-dropping position except when bottle carrier 110 is in raised position, a latch 380 is pivoted at the right hand edge of table 70. When carrier 110 is not in raised position, latch 380 will be lowered as shown in Figure 5 and a shoulder on the latch will bear against the end member 346 of the grid so that the grid cannot move to the right to drop bottles. When carrier 110 is in raised position, a fixed striker 382, which extends upwardly from carrier 110, will engage the free end of latch 380 to raise it out of engagement with the grid so that the latter may be moved to the right in due course to drop bottles.

As shown in Figure 1, the grid end member 346 is provided with a projection 384 adapted to contact a switch 386 mounted in a housing fixed to table 70. Such engagement occurs when the grid moves to bottle-dropping position and will cause switch 386 to open. The opening of 386 as well as the operation of other switches hereinafter described will result in downward movement of carrier 110 with the bottles deposited therein.

The bottle carrier

The bottle carrier 110 is shown in plan in Figure 14 and side elevational views thereof appear in Figures 5 and 15 to 18.

Referring to Figure 14, carrier 110 is of generally grid-like form in plan to thereby provide four relatively long openings, each of which, in the disclosed machine, is adapted to support six bottle holders. The front and rear sides of the carrier are defined by two parallel bars 390 which extend between the heavy brackets 391 which support the carrier. Inwardly of the brackets 391, the bars 390 are connected by end plates 392. Bars 393 parallel to the front and rear bars 390 extend between the end plates 392 to produce the grid-like form mentioned above. The bottle holders 102 are supported between the bars 390 and 393.

As best shown in Figures 21 to 25, each bottle holder includes two opposed plate members 394 which have their end portions inwardly offset as indicated at 395 in Figure 23. Two additional plate members 396 including inturned ends 397 form the other two sides of the bottle holder body. The four plate members are held together by means of machine screws which extend through the end portions of the members 394 and into the angled end portions of the members 396, the screws being threaded in two vertically extending straps 398 which lie inside the assembly. It will be observed that this arrangement permits the exterior of the bottle holder to be substantially square.

Each of the plate members 396 has a short lateral extension 400 on its upper edge which is adapted to rest on the bars 390 or 393 of carrier 110. As shown in Figure 18, a top plate 402 including circular apertures aligned with the bottle holders 102 may be secured to the top of the carrier to hold the bottle holders in place and prevent them from moving upwardly.

Each of the plate members 396 has a tongue 114 of resilient metal welded thereto and extending downwardly therefrom, the tongues 114 normally being straight as illustrated in Figures 21 and 25. The two plate members 394 have downwardly extending tongues 404 welded thereto, the tongues 404 being bent midway of their length as indicated at 405 so that their lower ends normally contact as illustrated in Figures 22 and 25. As is hereinafter described, the first-mentioned straight tongues 114 are adapted to be moved together by the cam rods 112 of Figure 17 to thereby retain bottles in carrier 110.

The heavy supporting brackets 391 on which carrier 110 is mounted are vertically movable in guideways 408 fixed to the frame of table 70, the guideways including channels or slots 410 in which rollers 412 mounted on the brackets 391 may move. As shown in Figure 17, a sprocket chain 414 has one end thereof secured to a cross member 415 which joins the two brackets 391, chain 414 moving over an idler sprocket wheel 416 journaled on a plate 417 fixed below the upper surface of table 70. The opposite end of chain 414 has the counterweight 124 secured thereto. Counterweight 124 moves between guides 124a and is of such weight with respect to the carrier 110 and bottles to be carried in the latter that carrier 110 will move downwardly against the action of the counterweight when it is filled with bottles. Upward movement of the carrier is effected by a piston rod 418 shown in Figure 4 which has its upper end secured to the carrier cross member 415. Piston rod 418 has a

piston movable by compressed air in the cylinder 419 fixed to the machine base. When air is admitted to the lower end of cylinder 419 the piston rod 418 and carrier 110 are elevated to bottle receiving position. When the flow of air to cylinder 419 is reversed, carrier 110 will be pushed down against the weight of counterweight 124.

Figures 17 and 18 are so positioned on the sheet which bears them that the vertical distance between the upper surface 72 of the table 70 of Figure 17 and the case conveyor 130 of Figure 18 is shown to scale. As shown in Figure 17, on its rearward side, carrier 110 has a vertically extending cam bar 110a fixed thereto. Figure 18 shows the carrier 110 in lowered position and thereby indicates how cam bar 110a, during lowering and raising of carrier 110, actuates two switches 632 and 780 with results discussed under the heading "Control circuits."

As is best shown in Figures 15 and 17, which view the bottle carrier 110 from opposite sides, and as is also shown in Figure 16, the end plates 392 of the carrier 110 have the bottle holder controlling cam rods 112 journalled therein, the cam rods extending parallel to the front of the machine. If the carrier is adapted to receive four rows of bottles, with each row parallel to the front of the machine, the carrier will be provided with five cam rods 112 so that all four rows of bottles will be gripped from two sides. It will be observed from Figure 16 that each cam rod 112 may be formed of round stock but with flats 420 spaced along the rods in alignment with the normally straight tongues 114. As is indicated in Figure 17, when the cam rods 112 are turned to cause the flats 420 to lie substantially horizontal, the edges of the flats will hold the lower portions of the tongues 114 inwardly against the edges of the tongues 404 so that a bottle cannot drop between the tongues.

Figure 18 shows the cams 112 rotated so that the flats 420 lie substantially vertical. In this position, the tongues 114 spring outwardly to lie in a vertical plane so that a bottle may drop. The angled tongues 404 are not sufficiently stiff or rigid to hold the bottles against dropping therethrough when the tongues 114 are thus released.

As best shown in Figures 17 and 18, the left-hand end of each cam rod 112 has a lever 422 fixed thereto and the lower edges of the levers 422 are connected by a link 424. As best shown in Figure 15, the right-hand end of the rearmost cam rod 112 has a bell crank 120 secured thereto. The upper arm of the bell crank carries a roller 426 and the lower arm of the bell crank is engaged by one end of a coil spring 122 having its other end secured to the adjacent carrier bracket 391. Bell crank 426 also is provided with a detent 430 which, when the carrier 110 is in raised position, is engaged by the latch 116 pivoted at 432 to the adjacent end plate 392 of the carrier. Latch 116 thereby holds the bell crank 120 and the cam rods 112 in such position that the bottle holders 102 will be closed. When carrier 110 moves downwardly to the dotted line position of Figure 15, the free end of latch 116 will strike the trip 118 fixed to the carrier guideway 403, the latch thereby being raised so that the detent 430 and bell crank 120 are freed. Spring 428 immediately will rotate bell crank clockwise to the position shown in Figure 15 so that the cam rods 112 will rotate in the same direction, thereby permitting the bottle holders 102 to open so that the bottles may drop into a case.

When the carrier 110 moves upwardly from the dotted line position of Figure 15 the roller 426 of bell crank 120 will engage the outwardly inclined cam surface 126 fixed to the frame of the machine. Therefore, bell crank 120 will be swung counterclockwise as the carrier rises. When the carrier reaches the upper position shown in solid lines in Figure 15, detent 430 will be facing upwardly so that latch 116 may drop of its own weight to latch bell crank 120 and the cam rods 112 in bottle holding position.

Case centering and clamping mechanism

As is illustrated in Figure 4, the case conveyor 130 ex-

5 tends across the front portion of the machine beneath the grid 90 and bottle carrier 110. The case conveyor may be of flat link type and preferably is guided and supported between horizontally extending beams 440 secured to the machine base. The beams 440 support an idler roll or sprocket 442 and a drive roll or sprocket 444, the latter being driven by a motor and gear reduction unit 446 through sprocket chain 448.

Figure 19 shows the case conveyor 130 in plan and it will be noted that the conveyor is somewhat wider than the width of the cases to be handled so that, as described below, a case entering the machine from the right-hand side will be carried on the forward portion of conveyor 130 but will leave the machine on the rearward portion of the conveyor. This action is obtained by providing the guide plate 134 above the rearward portion of the infeed side of the conveyor and mounting a similar guide plate 146 on the forward portion of the outfeed side of the conveyor. The guide plates 134 and 146 are secured 10 to the supporting beams 440. The adjacent ends of the guide plates 134 and 146 are spaced apart and the case centering and clamping mechanism 140 is mounted in this area.

Case clamping and centering mechanism 140 is best 15 shown in Figures 5, 6, 19 and 20. It includes an air cylinder 450 fixed at its inner end to the base frame of the machine. Cylinder 450 has a piston 452 reciprocable therein, the piston 452 extending from the inner end of the cylinder. Piston 452 has secured thereto a carriage 20 element generally designated 454. Carriage 454 is of generally U-shaped form as viewed in side elevation and, as best shown in Figure 6, includes an upper portion 456 which is adapted to engage a case C on conveyor 130 and push it rearwardly of the machine. The lower part 25 of carriage 454 is positioned below the upper run of conveyor 130 and comprises a plate like portion 458 (Figure 20) which includes downwardly extending bosses 460 slidable upon guide rods 462 secured in the frame of the machine.

The upper portion 456 of case pushing element 454 includes a horizontally extending flange 464 (Figure 6) on which case engaging rollers 466 are mounted. As is indicated in Figures 19 and 20, the rollers 464 are of such diameter that they project inwardly beyond the edge of the flange 464 to engage a case moving into the machine. The upper portion 456 of the pusher element includes an inwardly extending wall 468 at its left-hand end in which a plunger 470 is mounted, the plunger having a roller 472 mounted on its inner end. When the mechanism is in the case receiving position shown in solid lines in Figure 19, a case C entering the machine from the right will be directed by the guide plate 134 to a position such as shown in dot and dash lines and wherein the case C will abut against the roller 472 so that the forward movement of the case will be stopped. As is hereinafter described, the engagement of the case with roller 472 will move the plunger 470 to the left, thereby actuating a plunger-operated switch 136 mounted in a casing fixed to the guide plate 146. As is hereinafter described, actuation of switch 136 will cause case conveyor 130 to stop movement and also will cause the case pushing mechanism to move the case to the solid line position of Figure 19, plunger 470 thereby being moved inwardly of conveyor 130 and out of alignment with the plunger of the switch 136.

As shown in Figure 20, the inner end of piston rod 452 is secured to a rod 476 fixed in the lower and plate like portion 458 of the pusher element. The lower portion 458 and upper portion 456 are connected by the horizontal rods 478 which extend alongside of the plate like element 458 of the lower portion and thence forwardly. Downwardly extending legs 480 (Figure 6) on the upper portion 454 are secured to the forward ends of the rods 478. As has been indicated above, the lower portion 458 moves beneath the case conveyor 130 while the upper portion

456 moves above the case conveyor. The provision of the rods 478 and legs 480 enables the two elements to be secured together in such manner that they will clear the conveyor during inward movement.

The case centering mechanism includes a sleeve 482 which is slidable upon the inner end of the rod 476, sleeve 482 normally being held against a collar 484 fixed to the inner end of rod 476 by a coil spring 486 which surrounds rod 476. As is best shown in Figures 20 and 28, collar 482 has a pair of links 488 pivotally connected thereto, the links diverging from each other. At their opposite ends, the links are pivotally connected to relatively short arms 490 which extend radially from stub shafts 492 journaled in bosses 494 integral with plate like elements 496 which extend forwardly from the rearward conveyor supporting beam 440. The shafts 492 extend above the surface of the upper run of the case conveyor 130 and, as shown in Figure 19, have curved case centering arms 144 fixed to their upper ends.

As shown in solid lines in Figure 19, when the mechanism 140 is in readiness to receive a case, the carriage element 454 will be at the forward side of the path of the cases and the clamping arms 144 will be spread apart. When air is admitted to the cylinder 450 to urge the piston 452 and the carriage element 454 rearwardly, the resultant force thereby applied to the forward ends of the links 488 will cause the latter to rotate the vertical shafts 492 in opposite directions, thereby carrying the case clamping arms 144 to the position shown in dotted lines in Figure 19 when the inward movement of the case is completed. Rollers 500 journaled on pins fixed to the rearward beam 440 limit the inward movement of a case C with the clamping and centering mechanism 140.

It will be observed that the mechanism described above enables the cases C to be held stationary for lowering of bottles therein and, moreover, because the clamping arms 144 move symmetrically they accurately center a case with respect to the downward path of travel of the carrier 110. The provision of the spring 486 enables the case centering links 488 and sleeve 482 to be compensated in the event a case is slightly oversize.

Although the case illustrated in Figure 19 is of the partitioned type, it will be understood that the machine also is adapted to fill partitioned cardboard cartons, it being a frequent practice to place four such cartons within an open topped box.

When the case is pushed inwardly to the solid line position illustrated in Figure 19, the inner wall of the case will contact the carrier safety switch 502 positioned in a casing 504 secured to the inner beam 440. Such engagement will open the switch 502 and, as is hereinafter explained, when this occurs, and if other conditions are in order, the carrier 110 will lower.

During the latter portion of the downward movement of the carrier 110 to drop its bottles, the carrier will contact a switch 506. As is hereinafter described, this will result in the piston 452 moving outwardly to the solid line position of Figure 19 so that the case clamping arms 144 will release the case. Case conveyor 130 then will re-start and move the case to the left (on the rearmost portion of conveyor 130) and between the guides 146 and 148. Conveyor 130 may support cases C in direct contact with each other and, in this event, a second case simultaneously will move forward to engage the roller 472. In order to prevent the clamping arms 144 from swinging inwardly until the first and filled case has cleared the path of travel of the arms 144, a switch 150 is provided at the outfeed side of the machine. So long as the first case is in engagement with switch 150, the clamping and centering mechanism 140 will be held against operation.

If a long line of contacting cases is standing on the in-feed portion of conveyor 130 and on conveyors which feed thereto, when a case is released by the mechanism

140, the succeeding line of cases may move forward with such force that the first case of the advancing line contacts too forcibly with roller 472. In order to prevent too sudden movement of a line of cases, a case retarding arm 510 is pivotally mounted on the guide 134 in advance of the machine. Arm 510 is spring loaded to the position illustrated in Figure 19 and is under sufficient spring tension that it has a retarding action on the advancing cases. For example, as a case moves past arm 510, the arm will drag along the case wall to thereby retard forward movement. At the same time, the arm 510 will urge cases toward the guide plate 132 to thereby insure that cases will be positioned on conveyor 130 to contact the roller 472 which operates switch 136.

Control circuits

Figures 29 and 30 diagrammatically show the electrical controls of the apparatus, the views also including diagrammatic showings of such portions of the apparatus mechanisms as affect the circuit operation. In Figures 29 and 30 the contacts of all relays are shown in the position they occupy when the relay is de-energized.

The machine is supplied with current from power lines 530 and 532 under the control of a main switch 534. When switch 534 is closed, the lines 530 and 532 respectively will be connected to the main conductors 536 and 538. In order to supply current of lower voltage to the various relays, a step-down transformer 540 is in circuit with the conductors 536 and 538.

The subsequent circuit discussion assumes that bottle carrier 110 is held in raised position by the circuit controls subsequently described, that grid 90 is in bottle supporting position but with no bottles thereon, that the bottle pushing mechanism 80 is in bottle receiving posi-

35 tation, the bottle infeed gates 73 are open, and that the bottle infeed conveyors 50, 52 and 56 are operating so that bottles will move on conveyor 62 between the pushing bars 74.

When bottles first are delivered to the apparatus, that is, when bottle conveyor 62 is empty, all four rows between the pusher bars 74 and the divider plates 66 will tend to fill evenly primarily because the spring deflector plates 61 of Figure 2 then direct each entering bottle to a position on conveyor 62 such as shown at B¹ in Figure 2, viz., in partial alignment with the divider plates 66a. When the first bottle in a line indicated by each bottle at B¹ reaches distributor plate 64, it will be pushed across that plate on the same line by following bottles but thereby will engage the end 182 of a divider plate 66a. Hence, the leading bottle momentarily will be stopped, but the pressure of the immediately succeeding bottles thereon will shift it either to the right or the left so that it will enter a row on one side or the other of plate 66a. The pressure which the succeeding bottles apply to the leading bottle likewise will cause such succeeding bottles to be laterally shifted one way or the other on plate 64 so that they generally will be evenly divided among the four rows formed by the divider plates 66 and conveyor 62 will move them forwardly and between the arms 74 of the pusher mechanism 80.

Once the four rows between the pusher bars 74 and the divider plates 66 have completely filled, bottles will fill the distributor plate 64 with two rows on each side 35 of divider plate 180 by the same sort of action as described above. Then the next bottle moving on conveyor 62 along one of the lines indicated by the two bottles at B¹ will be deflected and stopped when it reaches the massed and stopped bottles covering the plate 64. 70 Such next bottle and the succeeding ones will shift laterally with respect to each other on conveyor 62 when they stop because none of them will approach plate 64 in direct alignment with a bottle on that plate, and, therefore, the area of conveyor 62 between the plates 75 58 and 64 will tend to fill by one bottle stopping near

central divider plate 180 and the next stopping near an outer guide 54, with the result that the areas between plates 58 and 64 will fill with double rows of bottles back to the switches 184 and 186 so that those switches will close with results described below. It will be observed that the switches 184 and 186 will be closed by bottles in the outside rows and those rows will tend to fill last. When the switches 184 and 186 close, pusher mechanism 80 will remove four lines of six bottles each from the mass accumulated on conveyor 62 and the gates 73 will close. When the gates 73 subsequently open as described below to pass another twenty-four bottles to fill the pusher bars 74, all of the bottles on conveyor 62 and distributor plate 64 will move forward but by that time bottles moving across distributor plate 58 normally will have accumulated sufficiently to promptly fill the space thus provided near the outfeed edge of plate 58 on conveyor 62. Because the deflector arms 61 are of spring metal, they can flex to enable two bottles abreast to pass. If the area of conveyor 62 immediately in advance of distributor plate 58 has not been filled by the moment conveyor 62 moves the bottles forward, the first bottle to move from plate 58 will come to a stop adjacent divider plate 180 and the next will stop adjacent an outer guide rail 54 to thereby fill up conveyor 62 near the switches 184 and 186 as indicated above.

It will be perceived that once the machine and conveyor 62 have received enough bottles to start one cycle, the normal infeed of bottles will keep the bottle-actuated switches 184 and 186 closed. The bottle engaged portions of the arms of those switches are relatively long, (about two bottle diameters) so that the switches may close even if there is a gap between the bottles. That is, a gap usually is unimportant because whenever any bottle engages the switches 184 and 186, there will be more than enough bottles between those switches and the gates 73 to meet the demands of a cycle of the machine, so a gap in bottles adjacent the switches will not be critical. In this connection, assuming that the machine is to place four rows of six bottles in a case, each row between the pusher bars 74 will contain six bottles. The distances along conveyor 62 from the gates 73 to the switches 184 and 186 may be as follows: Between the gates 73 and the distributor plate 64, each row may contain nine bottles, distributor plate 64 may have a length corresponding to three times the diameter of a bottle, and the area from plate 64 to the outfeed portions of the switches 184 and 186 may accommodate four rows of six bottles each. Therefore, approximately ninety-six bottles may stand between the plungers 76 of the pusher mechanism 80 and the switches 184 and 186 before the machine begins operation. With bottles then being steadily delivered to the machine by the conveyors 50 and 52 at a rate in accordance with the output of the bottle casing machine, for example, three hundred six ounce bottles per minute, it will be perceived that the portion of the conveyor 62 outwardly of the gates 73 always will have an adequate supply of bottles to keep the switches 184 and 186 closed so that the machine will be maintained in steady operation.

For convenience of reference, the following paragraphs relative to the circuit operation are consecutively numbered.

(1) Whenever the pressure of twelve bottles is acting upon the bottle actuated plungers 76 of the bottle pushing mechanism 80 and sufficient bottles are standing on conveyor 62 to close the switches 184 and 186, the inward movement of the plungers 76 to the position indicated at 76a in Figure 11 will release the trigger 246 illustrated in Figures 11 and 12 and diagrammatically shown in Figure 29. Hence, spring 248 will move trigger 246 downwardly as viewed in Figure 29 to permit the trigger switch 298 to close. However, as indicated above, this will not result in any operation unless the bottle

actuated switches 184 and 186 are closed. Moreover, in order to start operation, starting switch 584, which is a hand-operated snap switch, also must be closed.

(2) When the bottle actuated switches 184 and 186 close, the following circuit will be completed: From the lead 554 of the transformer secondary by leads 556, 558, 560 and 562 through closed switch 186, lead 564 to closed switch 184, leads 556 and 568 to the contact 570 of switch 332, which contact is closed because the pusher mechanism 80 is in bottle receiving position, by lead 572 to the coil of relay R4, then by leads 574 and 576 back to the transformer secondary. Until relay R4 is energized, the gates 73 cannot close nor can the movement of the trigger 246 be of any effect. Once R4 is energized, a holding circuit by-passing the bottle actuated switches 184 and 186 will be established through the coil of R4 as follows: From lead 560 (connected to one side of the transformer secondary) by lead 578 and the closed contact 580 of relay R4, and lead 582 to lead 568 and the closed contact 570 of switch 332. Hence, if either of the switches 184 or 186 then momentarily opens because of a gap in the bottles, the machine cycle which has started will not be affected.

(3) Obviously, with bottles in position to close the switches 184 and 186, sufficient bottles will be bearing on all of the plungers 76 to move the latter to position 76a of Figure 11. Therefore, trigger 246 will be released to be moved by spring 248 (downwardly as viewed in Figure 29) to thereby permit trigger switch 298 to close. The closing of trigger switch 298 will close the following circuit through the contact 584 of relay R4: From secondary lead 554 by leads 556 and 586 to closed starting trigger switch 554 and lead 590 to the closed contact 584 of relay R4 and lead 592 through closed trigger switch 298 and lead 594 to the coil of trigger relay R6 and then by leads 596, 574 and 576 to the transformer secondary.

(4) Parenthetically, if the operator wishes to energize trigger relay R6 independently of relay R4 and trigger switch 298 to thereby close the gates 73 and operate the pusher mechanism 80, he may do so by closing the emergency trigger switch 600, to thereby close the following circuit: From secondary transformer lead 554 by leads 556, 586, already closed starting trigger switch 554, leads 590 and 602 through closed emergency trigger switch 600 and by leads 604 and 594 through the coil of relay R6 and by leads 596, 574 and 576 to the other side of the transformer secondary.

(5) The energization of trigger relay R6 through the contact 584 of relay R4 described above in paragraph (3) will close the contacts of R6, the closing of contact 606 completing the following circuit: From secondary transformer by leads 556 and 608 through contact 606, leads 610 and 611 to the coil of gate relay R1 and by leads 612 and 576 to the other side of the transformer secondary.

(6) The energization of the coil of gate relay R1 will close its contact 614 to thereby close the gates 73. The circuit will be as follows: From the high voltage line 536 by lead 616, contact 614, lead 618 to the solenoid valve 620 and by leads 622 and 624 to the other high voltage conductor 538. The operation of solenoid valve 620 will cause compressed air to flow to the air cylinder 210 of the gate mechanism 68, thereby closing the gates 73. Therefore, the twenty-four bottles standing between the pusher bars 74 will be closed off from the remaining bottles on conveyor 62 and the latter bottles will be held against forward movement with conveyor 62.

(7) If bottle carrier 110 is in raised position in readiness to receive bottles and, therefore, the contact 630 of the grid and pusher return switch 632 is closed, the following circuit will be completed: From transformer lead 576 to the coil of relay R2, and by lead 634 to the already closed contact 636 of trigger relay R6, by leads 638 and 640 to the contact of switch 212 closed by the closing

of the gates 73 and by lead 642 to contact 630 of switch 632 and then by leads 644 and 646 to leads 586 and 556 to the secondary transformer lead 554.

(8) The energization of pusher relay R2 will close a series holding circuit therefor through its contact 648 and in parallel with the circuit through the contact 636 of the trigger relay R6 so that as long as the switch 212 is maintained closed by the gates 73 being closed, and if the carrier 110 is in raised position so that contact 630 of switch 632 is closed, the pusher mechanism 80 will move through its operating cycle. Contact 636 of trigger relay R6 may open if the bottle actuated switches 184 and 186 open to deenergize relay R4 but the holding circuit through contact 648 of pusher relay R2 will hold R2 energized.

(9) The energization of carrier relay R2 discussed immediately above will cause the following circuit to be closed to move the pusher mechanism 80 to thereby move the bottles to the grid 90: From high voltage conductor 536 by leads 616, 650 and 652 through the closed contact 654 of relay R2 by lead 655 to the valve operating solenoid 656 and then by leads 657 and 624 to the other high voltage conductor 538. This actuation of the valve solenoid 656 will cause compressed air to move to the pusher mechanism operating cylinder 300 so that the pusher mechanism 80 will move the bottles positioned between the pusher bars 74 to the grid 90. The manner in which a space is provided between bottles in each row during this movement has been discussed above under the head "The bottle pusher mechanism 80."

(10) If the operator wishes to move the pusher mechanism 80 independently of grid and pusher return switch 632 and gate switch 212, and after the trigger relay R6 has been energized, he may close emergency gate and pusher switch 658, thereby closing the following circuit: From transformer lead 554 by leads 556 and 586 to closed emergency gate and pusher switch 658, by leads 659 and 638 to the already closed contact 636 of trigger relay R6, and then by lead 634 through the coil of pusher relay R2 to transformer lead 576. This will operate solenoid valve 656 just as described in the preceding paragraph.

(11) When the pusher mechanism 80 begins movement, the gate release switch 306 will close due to movement of member 305 of Figure 8 away from the movable contact of 306. This will close the following circuit: From secondary transformer lead 554 through switch 306 and lead 662 to contact 664 of R1 and leads 666 and 611 to the coil of gate relay R1 and then by leads 612 and 576 to the other side of the transformer secondary. It will be observed that this is a holding circuit through the coil of gate relay R1 so that R1 cannot de-energize and, therefore, the gates 73 will be held closed until pusher mechanism 80 returns to its normal or bottle receiving position.

(12) When pusher mechanism 80 reaches the limit of its pushing stroke so that the bottles are standing upon the bottle supporting bars 92 of grid 90, the pusher mechanism will engage the grid switch 332 to move it from the position illustrated in Figure 29 so that its contact 570 will open and its contact 670 will close. The opening of contact 570 will break the circuit of paragraph 2, above, so that relay R4 will de-energize, thereby de-energizing trigger relay R6, which will cause its contacts 606 and 636 to open. The opening of contact 606 of trigger relay R6 will not affect gate relay R1 because the latter will be held energized by the holding circuit through still closed gate release switch 306 and contact 664 of relay R1 mentioned in paragraph 11. The opening of contact 636 of trigger relay R6 will not affect pusher relay R2 because of the holding circuit described in paragraph 8 through its contact 648 and the closed gate switch 212.

(13) The closing of grid switch contact 670 will complete the following circuit to thereby cause the grid 90 to move to bottle dropping position: From the trans-

former secondary lead 554 by leads 556, 558 and 672 through closed contact 670, lead 674 to one coil of the grid operating solenoid valve 370, and then by leads 678, 574 and 576 to the other side of the transformer. Grid 90 thereby will move to position its bottle supporting bars directly beneath the fixed guide bars 100 and the bottles will drop into the bottle holders 102 of carrier 110.

(14) It will be noted that the pusher mechanism 80 cannot move bottles to the grid 90 unless the carrier 110 is in raised position so that the contact 630 of the grid and pusher return switch 632 is closed.

(15) Even though the bottles drop into the carrier 110 as mentioned in paragraph 13, above, the carrier 110 cannot move down unless a case C has been centered beneath carrier 110 to open carrier safety switch 502.

(16) Before discussing the actions resulting from the downward movement of the carrier 110, it is desirable to point out that when an empty case C moves into the case clamping and centering mechanism 140, the case will close the case clamp switch 136, thereby closing a circuit through that switch, the normally closed case safety switch 150, the normally closed contact 506 of the case release and carrier return switch and contact 680 of the emergency carrier drop preventing switch 682, with the result that the case clamp relay R3 will be energized to close its contact. This circuit through the coil of R3 is as follows: From the transformer secondary lead 554 by lead 556, closed case clamp switch 136, leads 684 and 686 through closed case safety switch 150, lead 688 to the closed contact 506 of the case release and carrier return switch, lead 690 to closed contact 680 of the emergency switch 682 and by lead 692 to the coil of relay R3, and thence by leads 694, 574 and 576 to the other side of the transformer secondary.

(17) The energization of carrier relay R3 will close its contact 696 to thereby complete the following high voltage circuit through the coils of case clamp relay R7 and case conveyor relay R8: From conductor 536 by leads 698 and 700 to contact 696 of R3 and thence by leads 702 and 704 through the coil of case clamp relay R7 and then by leads 706 and 708 to the other conductor 538. The coil of case conveyor relay R8 will be energized through leads 710 and 712 in parallel with the circuit just described. The normally closed contact 714 of case conveyor relay R8 will open after a delay of a second or so and thereby will break the circuit to the case conveyor motor 446 so that the case conveyor 130 will stop movement now that a case has engaged case clamp switch 136. Case conveyor relay R8 contact 714 opens immediately but closes to re-start case conveyor 130 with a delay of a second or so. It will be observed that the manual switch 716 for the case conveyor is positioned between contact 714 and the power conductors 536 and 538.

(18) The energization of case clamp relay R7 mentioned in paragraph 17 will cause its contact 718 to close, thereby closing a high voltage circuit as follows: From conductor 536 by leads 698 and 720 through closed contact 718, and by lead 722 to the valve operating solenoid 724 to the other conductor 538. This operation of solenoid 724 will cause compressed air to flow to the cylinder 450 to thereby operate the case clamping and centering mechanism 140. Case clamp relay R7 closes with snap action but has a delay action of a second or so in opening.

(19) As soon as the case clamping and centering mechanism 450 moves the case out of engagement with the case clamp switch 136, the latter will open. However, the energization of case clamp relay R3 mentioned in paragraph 17, above, closed R3 contact 726 and the following holding circuit then set up to by-pass case clamp switch 136 through contact 726 will maintain R3 energized: From transformer lead 554 by leads 556 and 730 to closed contact 726 and then by lead 732 and closed

case safety switch 150 to lead 688 and closed contact 506, lead 690, closed emergency switch contact 680, lead 692 to the coil of R3 and thence by leads 694, 574 and 576 to the other side of the transformer secondary.

(20) Until now, the carrier 110 has been held up by reason of the pressure of compressed air acting in cylinder 419 upon the piston 418. The air pressure in cylinder 419 has been maintained by the position of the carrier solenoid valve 734, the solenoid valve being maintained in proper position because contact 736 of carrier relay R5 has been held closed by the following circuit through the relay coil: From transformer lead 576, leads 574 and 738 to the coil of carrier relay R5, then by leads 740, 742 and closed contact 744 to lead 746, and the normally closed contact of emergency carrier dropping switch 748. From the left-hand side (Figure 29) of switch 748, the holding circuit may extend through each of three parallel paths to transformer lead 554, as follows: (a) by lead 750 to carrier dropping switch 386 and leads 558 and 556 to transformer lead 554, (b) by leads 750, 754 and 756 to normally closed carrier safety switch 502 and then by leads 758, 730 and 556 to transformer lead 554, or (c) by leads 750, 754 and 760 to normally closed clamp arm safety switch 762 and then by leads 764, 730 and 556 to transformer lead 554. It will be observed that so long as any of the three parallel circuits of (a), (b) or (c) is closed, carrier relay R5 will be held energized to thereby maintain air in cylinder 419 to hold the basket raised. However, all three of circuits (a), (b) and (c) now have been broken. That is, circuit (a) through the carrier dropping switch 386 has been broken because the grid 90 has opened that switch. Circuit (b) has been broken because a case C has been pushed against switch 502 to open the latter. Circuit (c) has been opened because the links 488 have moved rearwardly to urge the case clamping and centering arms 144 to the dotted line position of Figure 19, thereby opening the switch 762 which is in the path of clamping travel of the links 488. Therefore, the holding circuit through carrier relay R5 has been broken. The resultant de-energization of that relay and the opening of its contact 736 will result in the carrier solenoid 734 operating to supply air from the cylinder 419 so that carrier 110 will be moved down against the action of the counterweight 124.

(21) If the operator wishes to prevent the carrier 110 from dropping, he may operate the emergency switch 682 from the position illustrated in Figure 30, thereby opening its contact 680 and closing its contact 766. The opening of contact 680 will hold case clamp relay R3 against energizing and thereby will prevent the case clamping and centering mechanism 140 from operating to position and center a case. The closing of the contact 766 will energize the carrier relay R5 with the result that the carrier will remain up or, if down, will move up. This circuit through contact 766 is as follows: From transformer lead 554 by leads 556, 730 and 768 through closed contact 766, leads 770, 772 and 740 through the coil of relay R5 and thence by leads 738, 574 and 576 to the other side of the transformer secondary.

(22) During downward movement of the carrier 110, the latch 116 will strike the trip 118 shown in Figure 15 to operate the cam rods 112 so that the bottles may drop from the carrier 110 to the case C.

(23) When the carrier 110 moves down at least far enough that the tops of the bottles are below grid 90, the lower end of the cam bar 110a fixed to carrier 110 (Figure 17) will engage the arm 633 (Figure 18) of the grid and pusher return switch 632, the contact 630 of that switch will open, thereby breaking the holding circuit to pusher relay R2 established in paragraph 8, above, so that the pusher solenoid valve 656 will deenergize and the pushing mechanism 80 will move back to bottle receiving position. The simultaneous closing of contact 76

774 of switch 632 will energize the grid operating solenoid valve 370 so that the grid will return to normal bottle supporting position. The last-mentioned circuit is as follows: From transformer lead 554 by leads 556, 586, 646 and 644 to contact 774, lead 778 to solenoid 370 and then by leads 678, 574 and 576 to the other side of the transformer secondary.

(24) When the carrier 110 nears the end of its downward travel, its cam bar 110a will operate the case release and carrier return switch 780 to open the circuit through the contact 506 and close the contact 782. As shown in Figure 18, this switch is fixed to the guide-way 408 in such position as to be operated by the carrier when the latter reaches the lower end of its stroke. Opening of the contact 506 will de-energize the case clamp relay R3 so that the case clamp relay R7 and the case conveyor relay R8 will de-energize. The de-energization of case clamp relay R7 will permit its contact 718 to open after a second or so delay, thereby breaking the circuit described in paragraph 18, above, so that the air circuit in case pushing and clamping cylinder 450 will be reversed, the case clamping arms 144 will release the case C and the case pusher will move outwardly. Therefore, the case C will be free to move with the case conveyor. When case conveyor relay R8 de-energizes, its contact 714 will close after a delay of a second or so and the case conveyor 130 will re-start to move the filled case from beneath the carrier 110 and simultaneously move an empty case toward case clamp switch 136. It has been pointed out above that the empty case cannot be moved and clamped by mechanism 140 until the filled case has moved clear of the case safety switch 150. The delays mentioned above in the opening of the contact of R7 and the closing of the contact of R8 will insure that the carrier 110 will be clear of the bottles in the case C before the latter moves.

(25) As mentioned in the preceding paragraph, when carrier 110 reaches lowered position, cam bar 110a closes contact 782 of the case release and carrier return switch 780. When contact 782 closes, it will complete the following circuit: From transformer lead 554 by leads 586 and 786 to the closed contact 782 and thence by leads 788, 772 and 740 to the coil of carrier relay R5 and by leads 738 and 574 to the other transformer lead 576. Therefore, R5 will be energized and its contacts 744 and 736 will close. The closing of contact 736 will establish a circuit to operate the carrier solenoid valve 734 to reverse the air flow to carrier cylinder 419, so that carrier 110 will be raised to bottle receiving position. The circuit through contact 736 is as follows: From conductor 538 by lead 790 to valve operating solenoid 734, then by lead 792 to closed contact 736, and by leads 794 and 698 to the other conductor 536. As stated above, the operation of solenoid valve 734 will cause cylinder 419 to raise carrier 110. The closing of the other contact 744 of relay R5 will set up the holding circuit through its coil described in paragraph 20, above, and including three parallel portions. At the moment, at least the portion (a) of paragraph 20 will be closed because the grid 90 will have moved back to bottle supporting position as described in paragraph 23, above, and carrier dropping switch 752 will be closed.

(26) When the carrier 110 moves upwardly to move the lower end of its cam bar 110a above and clear of the case release and carrier return switch 780, the contact 782 of that switch will open but, as stated in the preceding paragraph, its closing has resulted in the establishment of a holding circuit through relay R5. The closing of its other contact 506 will have no effect unless a case C has closed switch 136. If switch 136 is closed, the circuit described in paragraph 16 will be closed. When carrier 110 nears its uppermost position, its cam bar 110a also will move clear of the arm 633 of the grid and pusher return switch 632 so that the latter will be restored to the position shown in Figure 30, thereby breaking the grid

restoring circuit described in paragraph 23. The movement of contact 630 to closed position by the raising of carrier 110 will provide a path for the circuit of paragraph 7. Thus, an operating cycle of the machine is completed and another cycle may start.

(27) If the operator wishes to lower the carrier 110 independently of the automatic controls of the machine, he may open the emergency carrier drop switch 748, thereby breaking the circuit described in paragraph 20 so that the carrier relay R5 will de-energize and thereby cause carrier operating solenoid valve 734 to release the air in cylinder 419 which is holding the carrier 110 upwardly.

The bottle infeed conveyor motor 800 may be manually controlled by a switch 802. It will be understood that switch 802 as well as the other manually operable switches 534, 554, 600, 658, 682, 716 and 748 will be located at points on the machine convenient to the operator.

It will be observed that the apparatus described above attains all of the objects set forth in the opening portion of this specification.

The terminology used in the specification is for the purpose of description and not of limitation, the scope of the invention being indicated by the claims.

We claim:

1. In conveyor apparatus, a horizontal distributor plate including infeed and outfeed edges, conveyor means to support articles in the plane of said plate and movable with respect to said plate to convey articles in a direction transverse to one of said plate edges so that the articles will move up on the infeed edge of said plate and off its outfeed edge and back upon said conveyor means, guide means above said plate extending substantially parallel to the conveyor means path, said plate having a length at least as great as the article-dimension which extends lengthwise of said conveyor means, said guide means defining an article path wider than the transverse dimension of the article.

2. Apparatus of the character described in claim 1 wherein said guide means defines a path at least twice the transverse diameter of the articles.

3. Apparatus of the character described in claim 1 including means adjacent the outfeed edge of said plate to divide articles into two groups.

4. Apparatus of the character described in claim 1 including means adjacent the outfeed edge of said plate to divide articles into two groups, the portion of said conveyor at the outfeed edge of said plate being of increased width.

5. Apparatus of the character described in claim 1 including means adjacent the outfeed edge of said plate to divide articles into two groups, the portion of said plate between said divider means and the infeed edge of said plate having a length at least as great as the dimension of an article lengthwise of said conveyor means.

6. In apparatus for handling a plurality of rows of articles, a pair of conveyors, each of a width corresponding to the transverse dimension of the articles, a receiving conveyor at the outfeed portions of said first-mentioned conveyors, means to guide articles from said first-mentioned conveyors onto said receiving conveyor, said receiving conveyor having a width at least twice the transverse dimensions of the articles so that two articles may move thereon abreast, and means at the outfeed end of said receiving conveyor to form the articles into a greater number of rows than two.

7. In apparatus for handling a plurality of rows of articles, a continuously moving conveyor to support articles, means above said conveyor to segregate articles moving on the conveyor into a plurality of rows and to move the articles transversely of the conveyor, and means positioned alongside said conveyor responsive to the presence of articles thereon to control said last-named means.

8. In apparatus for handling a plurality of rows of

articles, a moving straight line conveyor to support articles, means above the article-supporting surface of said conveyor to form the articles into at least two rows, means to initially direct articles into one of said rows, means to remove the formed rows of articles from said conveyor, and means responsive to the presence of articles in the other of said rows to control the operation of said last-named means.

9. Apparatus of the character described in claim 8 wherein said first-mentioned means forms the articles into at least three rows and said means to direct articles initially directs articles to an inner row.

10. In an apparatus for handling groups of articles arranged in rows, a moving article supporting conveyor, means above said conveyor to form articles in an even number of rows, means to direct articles to said last-named means to fill inner rows in advance of the other rows, means to move articles from said conveyor means, and means to control the operation of said last-named means responsive to the presence of articles in the outer rows.

11. In apparatus of the class described, article conveying means of straight-line type including a first portion to support a relatively small number of rows of articles abreast and a second portion to support a larger number of rows abreast, distributing means between said portions to distribute the articles on said first portion transversely of said second portion, guide members on said second portion to segregate the rows of articles moving thereon, said distributor means including an element to direct articles into contact with the infeed end of one of said guide members.

12. Apparatus of the character described in claim 11 including a second distributor means between said second portion of said conveyor means and said guide members.

13. In apparatus to place articles in cases, a table structure, endless conveyor means movable across the top surface of said table structure, means movable transversely of said conveyor means and adapted to receive articles and form them in a plurality of rows extending longitudinally of said conveyor means, a plate including infeed and outfeed edges extending across said conveyor means adjacent the infeed end of said last-named means, said plate including an upper surface substantially flush with the article-supporting surface of said conveyor means so that articles will move off said conveyor means onto the infeed edge of said plate and then move off the outfeed edge of said plate back onto said conveyor means, and guide means alongside said conveyor means in advance of said plate, said guide means being spaced apart by a distance at least twice the transverse dimension of the articles.

14. Apparatus for forming a plurality of rows of round articles into a greater number of rows comprising conveyor means, guide means alongside a first portion of said conveyor means to provide an article path at least twice the diameter of the articles, a first plate extending across the outfeed end of said first conveyor portion and including an article-supporting surface substantially flush with the article-supporting surface of said conveyor means so that articles will move from said first portion of said conveyor means onto said plate and then will move back onto a second portion of said conveyor means, guide means alongside said second portion of said conveyor means, a central divider member extending longitudinally of said second portion of said conveyor means midway of said guide means, said central divider means being spaced from each of said guide means by a distance at least twice the diameter of the articles, a second plate extending across the outfeed end of said second portion of said conveyor means beyond the outfeed edge of said second plate to form articles moving from said second plate into a plurality of single rows.

15. In apparatus for forming articles into rows, a continuously moving conveyor to support rows of articles,

guide plates extending lengthwise of and above the article-supporting surface of said conveyor means to separate adjacent rows, and means to control the feed of articles between said guide plates comprising a support extending above said conveyor means, a plurality of gate members respectively rotatable in said support about a vertical axis lying in the plane of a guide plate, each of said gate members being of planar form so that it may lie in the plane of the corresponding guide plate, and means to rotate said gate members between open position and article stopping position.

16. In apparatus of the class described, a table structure including first and second article-supporting areas, means to deliver a group of articles to said first area, means to move the articles to said second area, said bounding means being carried by said means to move articles to said second area, means to bound said first area, and means to move said bounding means to enlarge the bounds of said first area before the articles reach said second area.

17. Apparatus of the character described in claim 16 wherein said bounding means is movable to enlarge said first area in a direction normal to the direction of movement of said article moving means.

18. Apparatus of the character described in claim 16 wherein said means to move articles to said second area is a reciprocable conveyor.

19. In apparatus of the class described, a table structure including first and second supporting surfaces for a row of articles, said surfaces being adjacent each other in a direction normal to the length of said row of articles, said second supporting surface being provided with article-supporting bars extending normal to said row of articles, the infeed end of said bars lying along a V-line having its apex facing said first surface, means to form a row of articles on said first surface, means to bound the ends of the row, means to move the row of articles from said first to said second surface and to space apart said bounding means.

20. In apparatus of the class described, a table structure including first and second supporting surfaces for a row of articles, said surfaces being adjacent in a given direction, means to form a row of articles on said first surface, said last-named means including row-end bounding members, means on said second surface to space apart the articles in the row, and means to move the row of particles from said first to said second surface and move one of said bounding members away from the other.

21. In apparatus of the class described, a table structure, a guideway on said table structure, a housing reciprocable on said guideway, article row-forming members extending from said housing above said table structure, means to move articles between said members, row-limiting means on said housing to define a line extending transversely of said members, and means to move said last-named means toward said housing and move said housing along said guideway.

22. Apparatus of the character described in claim 21 wherein said row-limiting means comprises a plurality of plungers, one between adjacent article row-forming members.

23. Apparatus of the character described in claim 21 wherein said row-limiting means is initially movable by pressure of articles thereon and such initial movement controls feed of articles to said article row-forming members.

24. Apparatus of the character described in claim 21 wherein said means to move said row-limiting means toward said housing is effective on movement of said housing on said guideway in one direction, and means to move said row-limiting means away from the housing when the latter moves in the opposite direction.

25. In apparatus of the class described, a table, an article conveyor movable on said table, an article-engageable member reciprocable on said conveyor and

adapted to be moved by an article, a trigger normally held by said member against movement, and means to supply articles to said conveyor controlled by movement of said trigger.

26. Apparatus of the character described in claim 25 including means to move said article-engageable member to a second position.

27. Apparatus of the character described in claim 25 including means to move said conveyor controlled by the operation of said article-supplying means.

28. In apparatus of the class described, a table, a guideway on said table, a first element movable on said guideway, a member reciprocable on said first element and adapted to be engaged by an article, a trigger normally held by said member against movement, a second element movable on said guideway and connected to said first element, means to move said second element on said guideway rendered operative by release of said trigger, and means connected to said second element and to said member to move the latter further upon movement of said second element on said guideway with respect to said first element.

29. In a machine to place articles in cases, a table, article-moving means reciprocable across said table, a carrier vertically movable below said table to receive articles from said article-moving means when the latter is moved toward said carrier, and means controlled by downward movement of said carrier to move said article-moving means away from said carrier.

30. In a machine to place articles in cases, a vertical frame, means on the upper portion of said frame to support articles, an article carrier vertically reciprocable in said frame below said first-named means to receive articles therefrom, said carrier including article-holding elements, rotatable members to maintain said elements in engagement with the articles, means to urge said members to a position to free said elements, a latch on said carrier to hold said members against movement to said position, and means on said frame in the path of travel of said carrier to release said latch.

31. A machine of the character described in claim 30 including means on said frame to re-set said rotatable members to latched position.

32. In a machine to place articles in cases, a table, an article-supporting element in said table and movable between article-supporting and non-supporting positions, a carrier vertically movable in said table to receive articles from said element when the latter is moved to non-supporting position and carry the articles downwardly, and means operated by downward movement of said carrier to move said element to its supporting position.

33. In a machine to place articles in cases, a table, a case conveyor movable beneath said table, a carrier vertically movable in said table to carry articles to a case on said conveyor, means to stop said conveyor when a case is supported beneath said carrier, and means to re-start said conveyor upon downward movement of said carrier.

34. A machine of the character described in claim 33 wherein said conveyor re-starting means includes a delay element.

35. In an article casing machine, table means to support articles, a case support below said table means, a case pusher element reciprocable across said case support, a pair of links pivoted to said pusher element and diverging from each other in the direction of case pushing movement of said pusher element, a pair of rotatable case-engaging members pivoted on said table means, the free ends of said links respectively being operatively connected to said members to move the latter toward each other when said pusher element moves in one direction across said case support.

36. A machine of the character described in claim 35 including a resilient connection interposed between said case-engaging members and said case pusher element.

37. Apparatus of the class described, a table, a guideway in said table, an article conveyor including a housing reciprocable on said guideway, an article-contacted member reciprocable toward and away from said housing, means to move said housing on said guideway actuated upon given movement of said member toward said housing, and means to move said member further toward said housing operated by movement of said housing along said guideway.

38. Apparatus of the character described in claim 37 wherein said means to move said member further toward said housing includes an element movable on said guideway.

39. Apparatus of the character described in claim 37 wherein said means to move said member further toward said housing includes an element movable on said guideway, and a lever pivoted in said housing and connected to said element and member.

40. In apparatus for placing articles in a case, a table including an upper horizontal surface, a reciprocable pusher movable across said surface, said pusher including a plurality of row-forming parallel arms with adjacent arms spaced apart to receive a row of the articles therebetween, the bars being of such number as to receive rows corresponding in number to the rows receivable in the case to be filled, means to deliver articles simultaneously between all of said arms and to limit delivery between adjacent arms to the number of articles receivable in a row in the case, means beneath said table to support a case, and means to move said pusher across said table to a position above the supported case and then return the pusher to article-receiving position.

41. Apparatus of the character described in claim 40 wherein said means to simultaneously deliver articles between said arms includes a conveyor movable in said table beneath and in a direction parallel to said arms, said conveyor having a width at least sufficient to support the number of rows of articles receivable between all of said arms.

42. In a machine for placing articles in cases, a table provided with an opening in its upper surface, article-engaging parallel plates fixed to said table and extending across the table opening, an article-supporting member of grid-like form to include bars parallel to said plates, said member being mounted in the table opening below said plates, means to move said member horizontally between a first position wherein its bars are in vertical alignment with said plates and a second position wherein its bars are out of alignment with said plates, an article carrier vertically reciprocable in said table below said member, a latch associated with said table movable to engaged position to prevent movement of said member to said first position, and means on said carrier to disengage said latch when said carrier is raised.

43. In apparatus of the class described, a table structure, a guideway on said table structure, a housing horizontally reciprocable of said guideway, article row-forming members extending from said housing above said table structure, row-limiting means on and movable toward and away from said housing to define a line extending transversely of said members, holding means to prevent movement of said row-limiting means toward said housing, means to move articles between said members to release said holding means, and means to move said housing and articles engaged by said members in one direction along said table, move said row-limiting means toward said housing, and then move said row-limiting means away from said housing.

44. Apparatus of the character described in claim 43 wherein said last-named means includes a rotatable cam carried by said housing to re-set said holding means, and means on said table to operate said cam.

45. In apparatus of the class described, a table structure including first and second article-supporting areas,

means to deliver a group of articles in rows to said first area, transfer means movable on said table structure to move the articles transversely of the rows to said second area, means to operate said transfer means, means to bound one side of said first area along a line parallel to that along which the articles are moved to said second area, said bounding means being carried by said means to operate said transfer means, and means to move said bounding means in the direction of the article rows to enlarge said first area.

5 46. Apparatus of the character described in claim 45 wherein said means to move the articles to said second area includes a plurality of row-forming arms secured to an element reciprocable upon said table structure between said first and second areas.

10 47. Apparatus of the character described in claim 45 wherein said means to move the articles to said second area includes a plurality of row-forming arms secured to an element reciprocable upon said table structure between said first and second areas, and said bounding means includes an article-engaging member horizontally reciprocable with respect to said table structure and reciprocable element.

15 48. Apparatus of the character described in claim 45 wherein said means to move the articles to said second area includes a plurality of row-forming arms secured to an element reciprocable upon said table structure between said first and second areas, said bounding means includes an article-engaging member horizontally reciprocable with respect to said table structure and reciprocable element, and means to move said bounding means before said reciprocable element moves from said first area.

20 49. In apparatus of the class described, a table structure including first and second article-supporting areas, means to deliver a group of articles to said first area, means to move the articles to said second area, said bounding means being carried by said means to move articles to said second area, means to bound said first area, and means to move said bounding means to enlarge one side of said first area in a horizontal direction before the articles are moved from said first area.

25 50. In apparatus of the class described, a table, a first article conveyor movable across said table, means to move said first article conveyor, a second article conveyor to deliver articles to said first conveyor, gate means to control delivery of articles to said first conveyor, article-engageable means carried by said means for moving said first conveyor and positioned in the path of movement of articles with said second conveyor and on the outfeed side of said gate means, and means to close said gate means and then move said article-engageable means in the direction of travel of said second conveyor to increase the distance between said article-engageable means and said gate means.

30 51. In apparatus for placing articles in a case, a table including an upper horizontal surface, a reciprocable pusher movable across said surface, said pusher including a plurality of row-forming parallel arms with adjacent arms spaced apart to receive a row of the articles therebetween, the bars being of such number as to receive rows corresponding in number to the rows receivable in the case to be filled, means to deliver articles simultaneously between all of said arms, means to limit delivery between adjacent arms to the number of articles receivable in a row by the case, means beneath said table to support a case, means to move said pusher across said table to a point above the supported case and then return the pusher to article-receiving position, electrical circuit means to cause said operations to follow cyclically when a number of articles at least as great as the case capacity are carried by said article-delivery means, said circuit means including a switch responsive to the presence between said switches and said pusher on said

article-delivery means of a number of articles substantially in excess of the capacity of a single case being filled.
